TORQUE AND WEIGHT CONTROL APPARATUS

Kenneth A. Summers, Los Angeles, Calif.

Application October 18, 1954, Serial No. 462,700

1 Claim. (Cl. 255—28)

2

The problem of careful weight and torque control also exists in bore hole milling and cutting operations. In every instance, the operation is manually controlled from the surface of the bore hole and is, accordingly, subject to human error.

Bearing the above in mind, it is a primary object of the present invention to provide a tool in which the torque and weight on a drill bit or other member driven by a rotary driving means, is automatically controlled, whereby constant vigilance during a drilling operation is not necessary and the possibilities of damaged bits and twisted pipe strings are materially reduced.

More particularly, an object of the invention is to provide a tool for automatically maintaining the torque applied to a drill bit or cutting member substantially constant.

A further object is to provide a device of the above nature which is rugged and simple in construction, and which may be readily adapted to conventional bore hole drilling apparatus without modification of any of the existing equipment.

These and other objects and advantages of this invention are realized by providing a pair of telescoping elements adapted to be inserted between the rotary driving means and the driven member, such as a drill bit. These elements include means automatically responsive to an increase in the resistance to rotation of the bit beyond a given torque value, for telescoping the elements together, whereby the bit is retracted slightly from the earth formations and the resisting torque is brought back to said given value. A further means is provided for maintaining the axial force or weight acting on the bit substantially constant so that the applied torque will not appreciably vary.

In a preferred form of the invention, one of the elements comprises a cylindrical section. The other element comprises a mandrel supporting the drill bit at its lower end and having its upper portion fitted partially within the cylindrical section for telescoping movement. The free end of the cylindrical section is secured to the end of a string of drill pipe. The mandrel is provided about its periphery with one or more grooves spiraling towards the drill bit end of the mandrel in the direction of normal rotation of the driving means. Cam means are stationarily secured to the cylindrical section and arranged to project into at least one of the grooves. Circulating mud pressure passing through the cylindrical section is preferably employed to control the axial force or weight applied to the drill bit. This control is accomplished by providing a restricting orifice in the mud passage passing through the mandrel so that a pressure differential exists between the upper and lower ends of the mandrel. This pressure differential will thus tend to normally urge the grooved mandrel axially from the section towards the earth formations. In certain types of operations, in which circulating mud is not available, the axial force or weight on the bit may be controlled by a compression spring disposed within the cylindrical section and normally acting between the mandrel and section to urge the mandrel outwards in the direction of the earth formations.

With the above described arrangement, an extraordinary resistance to rotation of the drill bit will result in the bit being held rotationally stationary with respect to the rotating pipe string and cylindrical section. As a result, the cam means will travel in the spiral groove, thereby telescoping the grooved mandrel into the cylindrical section to retract the drill bit slightly from the formations. This retraction will decrease the resistance of the formations to rotation of the bit whereby the torque component of force applied to the grooved mandrel and bit by the cam means will be sufficient to rotate the bit, and the drilling operation can continue.

This invention relates to an apparatus adapted to be inserted between a rotary driving means and a driven member for controlling the torque and axial force applied to the member. A preferred application of the invention is in controlling the torque and weight applied to a high speed drill bit in a bore hole drilling operation, and the apparatus will be described in this connection. It is to be understood, however, that the principles of operation are applicable to other types of rotary tools, such as drill pipe cutters, milling tools, and the like.

For maximum efficiency in a rotary drilling operation in a bore hole, it is important that the applied torque transmitted to the drill bit through rotation of the drill pipe string, be maintained substantially constant. If the applied torque is too small, the cutting blades of the drill bit will not be operating at maximum efficiency in cutting into the earth formations, and the drilling will be unnecessarily prolonged. On the other hand, if the applied torque exceeds a given value, the bit blades may be seriously damaged. In fact, if the resisting torque offered to the drill bit by a particularly hard formation is sufficient to hold the bit against rotation, the applied torque may increase to such a value as to twist off the drill pipe string.

The problem of maintaining constant torque is particularly serious in the case of high speed drilling operations such as those using a diamond core bit. Too much torque on a bit of this type oftentimes results in the diamonds being broken loose from their settings, thereby necessitating costly replacements.

The desired value of the torque to be applied and maintained constant for maximum drilling efficiency, depends upon the type of drill bit used and the strength of the driving drill pipe string. For example, it may be found that the pipe string and bit may tolerate a torque sufficient to result in three to four rotations of the upper end of the drill pipe before the drill bit at the lower end commences rotating. In this case, it is necessary to insure that the applied torque on the pipe string will not exceed this desired torque value if twisting off of the pipe string or damaging of the bit is to be avoided.

The applied torque on a drill bit is ordinarily controlled by the effective weight of the drill pipe string acting on the bit. This effective weight is, in turn, controlled by the supporting traveling block at the surface of the bore hole. In an endeavor to maintain the applied torque constant to attain maximum drilling efficiency and avoid broken bits and twisting off of drill pipe strings, a tension scale, interposed between the traveling block and pipe string, together with a suitable torque indicator, is carefully observed during a drilling operation. If the applied torque appears to be increasing beyond a given value, the effective weight of the drill pipe string may be decreased by lifting up slightly on the pipe string with the traveling block, thereby decreasing the frictional force of the cutting blades against the formations. If the torque appears to be decreasing, more weight or axial force is applied to the bit by lowering the traveling block.

If the earth formations are exceedingly soft so that the resisting torque offered to the drill bit is decreased, the axial force exerted by the mud pressure or compression spring will urge the grooved mandrel and bit further in the formations until the resisting torque is in equilibrium with the applied torque component exerted on the mandrel by the cam means. Thus, regardless of the variations in resisting torque offered by the formations, the axial weight or force and torque applied to the drill bit will be automatically adjusted to insure that the driving torque remains substantially constant.

A better understanding of the invention will be had by referring to the accompanying drawings in which:

Fig. 1 is an enlarged cut-a-way perspective view showing the torque and force control apparatus of the invention in operative position between a drill pipe string and drill bit during a drilling operation; and,

Fig. 2 is an enlarged view of a portion of the apparatus looking in the direction of the arrow 2 of Fig. 1.

Referring to Fig. 1, there is shown a bore hole 10 containing a string of drill pipe 11 for rotating a high speed drilling bit 12. Interposed between the lower end of the drill pipe and bit there is provided, in accordance with the invention, a torque and weight control apparatus designated generally by the numeral 13. As shown, this apparatus comprises a pair of telescoping elements, respectively in the form of a cylindrical section 14 and mandrel 15. The upper end of the cylindrical section 14 is secured to the lower end of the drill pipe string 11 as by screw threads 16. The lower end of the cylindrical section, on the other hand, is provided with a collar 17 having a reduced diameter bore coaxially aligned with the cylindrical section 14 and providing an inner annular shoulder 18.

The mandrel element 15 is telescopically guided into and out of the cylindrical section by the collar 17. The upper end of the mandrel is provided with an enlarged head portion 19, having a diameter corresponding substantially to the inside diameter of the interior of the cylindrical section so that an annular seal between the head and interior walls of the cylindrical section is attained. The underside of the enlarged head 19 defines a downwardly directed annular shoulder 20 adapted to abut the shoulder 18 when the mandrel is in its lowermost position and thereby serve as a stop. The lower end of the mandrel is threaded to secured to the drill bit 12 as shown.

The main body portion of the mandrel 15 is provided with at least one peripheral groove 21 spiraling towards the drill bit in a direction corresponding to the direction of rotation of the drill pipe string 11. In Fig. 1 this direction is clockwise as viewed looking down the bore hole from the top, and as indicated by the arrow. A projection 22, which may be in the form of an internal spline, integral with the collar 17, projects into the groove 21. With this arrangement, relative rotation between the mandrel and the cylindrical section will cause the projection 22 to ride in the spiral groove 21 and telescope the mandrel into and out of the cylindrical section.

In the embodiment of Fig. 1, there is shown a compression coil spring 23 positioned between the upper end of the mandrel head 19 and the top portion of the cylindrical section. This spring will normally urge the mandrel downwardly towards the earth formations. In drilling operations such as illustrated in Fig. 1, however, the principal axial force applied to the mandrel 15 is derived from the circulating mud pressure. This mud flow generally passes downwardly through the interior passage 24 of the drill pipe, through the hollow interior of the cylindrical section 14, through an internal bore 25 in the mandrel 15 and out the drill bit 12. The mud then carries up chips and other debris churned up by the bit outside the drill pipe to the surface of the bore hole 10. In order to employ the mud flow pressure for exerting an axial force on the mandrel, there is provided a restricting orifice 26 in the bore 25 of the mandrel head 19. There will then be established a pressure differential between the upper

and lower ends of the mandrel which may be varied by varying the mud pressure.

In operation, the weight and torque control apparatus 13 and drill bit 12 are lowered into the bore hole 10 by the traveling block (not shown) in the conventional manner. During this lowering operation, the mandrel 15 is normally telescoped downwardly by the spring 23 or mud pressure until the shoulder 20 is seated against the shoulder 18. When the drill bit 12 engages the bottom of the bore hole, continued lowering of the pipe string will cause the cylindrical section 14 to telescope over the mandrel, and the entire pipe string and cylindrical section will rotate in a clockwise direction, and the projection 22 will downwardly spiral within the groove 21. When the mandrel head 19 reaches a substantially centered position within the hollow interior of the cylindrical section 14, the drill pipe string and cylindrical section are held against further movement in a vertical direction by the traveling block at the surface. The pipe string and cylindrical section are then caused to rotate in a clockwise direction by the rotary table at the surface. This rotary motion is transmitted to the mandrel 15 and drill bit 12 by the cam means or projection 22 engaging the upper surface of the groove 21.

In order to understand the relationship between the various forces acting on the mandrel and drill bit, reference is had to Fig. 2. In this drawing, the projection 22, upon rotation of the cylindrical section 14, will be moving to the left and thus bearing against the upper edge of the groove 21. The total force exerted by the projection against the groove 21 is indicated by the vector 27. This force will act in a direction normal to the tangential contact of the projection on the upper edge of the groove. Assuming the helix angle of the grooves to be 30 degrees, for example, the vector 27 will be at a 30 degree angle with respect to the vertical. This force vector may be divided into a horizontal force component 28 and a vertical force component 29. The vertical component 29 tends to lift the mandrel 15 up into the cylindrical section 14, while the horizontal component 28 tends to rotate the mandrel. This horizontal component therefore represents the torque applied to the mandrel and drill bit.

Under equilibrium conditions during a drilling operation, it will be clear that the axial force applied to the mandrel by the circulating mud pressure differential across the orifice 26, plus any axial force exerted by the compression spring 23, when such a spring is employed, exactly balances the upward component of force 29 resulting from the pressure of the projection 22 on the groove, plus the upward reaction force exerted by the formation on the drill bit. Also, it will be clear that the resistance to rotation of the drill bit by the formations will establish a reacting or resisting torque which will balance the horizontal torque component 28. The magnitude of the applied horizontal force component 28 may be controlled by the axial force brought to bear on the mandrel by the circulating mud pressure. For example, by increasing this axial force, the total contact force between the mandrel groove 21 and the projection 22 as represented by the vector 27 is increased. Correspondingly, the horizontal and vertical components 28 and 29 are increased. The increased vertical component balances the increase in the axial force so that there is no change in the axial force applied to the drill bit, while the increased horizontal component provides the desired increased torque. Since the vertical forces are in balance, the mandrel and section will rotate as a unit.

With the mud pressure adjusted to provide a torque component 28 of desired value, the drilling progresses in the normal manner. Should the resistance to rotation of the drill bit increase suddenly as a result of a particularly hard formation, this increased resistance will tend to hold the mandrel rotationally stationary with respect to the rotating cylindrical section 14. As a result, the projection 22 will move in the groove 21 to the left,

as viewed in Fig. 2, and thereby lift the mandrel into the section. This lifting action is a result of the increased torque resistance on the drill bit. Referring to Fig. 2, it will be evident that such an increase will require an increased balancing torque component 28. This increased component is supplied by the rotary table at the surface, but will immediately result also in an increased lifting component 29. Since the mud pressure acting on the mandrel is held constant, this increased lifting component will cause the mandrel to move into the cylindrical section. This telescoping movement in turn will retract the drill bit 12 slightly from the formations and thereby decrease the resisting torque offered to the bit by the formations. When this resisting torque has decreased to the desired torque value represented by the horizontal vector 28, the vertical force component 29 will again be in equilibrium with the axial force exerted on the mandrel by the mud pressure, and the mandrel and cylindrical section will again commence to rotate as a unit.

In the event the earth formations are unusually soft, the axially directed reacting force of the formation on the drill bit tending to urge the mandrel into the cylindrical section, will decrease. Since the circulating mud pressure is held constant, and will now be greater than this reacting force, the mud pressure force will commence urging the mandrel further into the formations by spiraling the mandrel ahead of the normal movement of the projection 22. As soon as the reacting force of 29, again balance the downwardly directed mud pressure force, all of the vertical forces will be in equilibrium and the mandrel and cylindrical section will rotate as a unit.

It should be noted that, as a result of the telescoping construction of the mandrel and cylindrical section and the transmission of the driving torque by the cam means as described above, the weight and torque on the drill bit are held substantially constant throughout an entire drilling operation regardless of variations in the hardness of the formations.

As the drilling progresses, it will be understood, of course, that the traveling block is lowered to follow the progress of the bore hole and maintain the mandrel block 19 in a substantially centered position in the interior of the cylindrical section 14.

In certain drilling or cutting operations, circulating mud may not be available. In this instance, the compression spring 23 can be made sufficiently strong to provide the desired axial force on the mandrel. An increase in

this force will occur if the mandrel is telescoped any appreciable distance from its original position in the cylindrical section, but this increased force due to the characteristics of the spring will not be significant, provided the telescoping movements of the mandrel within the cylindrical section are only a small per cent of the total length of the spring.

In other instances, it may be desirable to have an increased axial force in response to telescoping movement of the mandrel within the section, thereby providing an increased torque. In such cases, the helix angle could be changed to result in increased telescopic movements and the compression spring would then provide an increased torque component.

While the invention has been described with respect to a drilling operation, as mentioned previously, it is to be understood that the principles are applicable for controlling the torque and axial force applied to any member driven by a rotary driving means. The torque and force control apparatus is therefore not to be thought of as limited to the specific embodiment described and illustrated.

What is claimed is:

- 25 An apparatus for controlling the torque and weight applied to a driven member by a rotary driving means in a bore hole operation, comprising: a cylindrical section; a mandrel fitted partially within said cylindrical section for axial telescoping movement within said section, the free end of said section being coupled to said rotary driving means and the free end of said mandrel being secured to said driven member, said mandrel having at least one peripheral groove spiraling towards said driven member in the direction of rotation of said driving means; cam means stationarily secured to said cylindrical section and projecting into at least one of said grooves; fluid passage means passing through said mandrel and said cylindrical section for circulating drilling fluid therethrough; and pressure means for applying a predetermined force on said mandrel in the axial direction of said driven member
- 30 comprising a restricting orifice in the fluid passage means in said mandrel, whereby fluid pressure is exerted on said mandrel.
